PLUGGING DEVICE FOR DOOR LOCKS

Paul Sevčík, Chicago, Ill.

Application December 18, 1947, Serial No. 792,536

8 Claims. (Cl. 70—428)

1

My invention relates to door locks of the mortise type, and more particularly to those found in hotels, rooming houses and the like. Such locks usually receive a skeleton key, and therefore offer little security against unauthorized entrance to the premises. It is therefore one object of the present invention to provide a device which an occupant can use for plugging the keyholes of the lock when retiring or leaving the premises, so that it will be impossible for anyone to insert a key into the lock from the outside.

A further object is to provide a unit which is insertible into the lock from the outside or the inside by way of the keyhole and has a control for expanding the unit inside the lock to constitute a plug for the same.

Another object is to provide a control which is easily removable from the plugging device by the user thereof, whereby to leave no projection or sign in front of the door which may invite curiosity or tampering.

An important object is to provide the device with few and simple parts and in a manner to admit of fine variations and combinations in its control, in order to prevent the easy duplication thereof.

With the above objects in view, and any others which may suggest themselves from the description to follow, a better understanding of the invention may be had by reference to the accompanying drawing, in which—

Fig. 1 is a side elevation of the lock as mounted in a fragment of a door;

Fig. 2 is a section on the line 2—2 of Fig. 1, showing the plugging unit and its control separated therefrom;

Fig. 3 is an enlarged elevation of the device, showing the control fitted in the plugging unit, and the latter in the normal or contracted positions;

Fig. 4 is a bottom plan view of the showing in Fig. 3, with the control partly broken away;

Fig. 5 is an enlarged section on the line 5—5 of Fig. 3, partly in elevation and in the plugging position;

Fig. 6 is a vertical section of the showing in Fig. 5; and

Fig. 7 is a cross section on the line 7—7 of Fig. 6.

In accordance with the foregoing, specific reference to the drawing indicates a conventional mortise lock at 10, the same having registering keyholes 11 and being fitted in a door 12.

The novel plugging device is mainly made up

2

of a housing 15 and a control key 16. Ordinarily the plugging unit is carried by the key 16, and Fig. 2 shows that such unit has been inserted to pass through the lock 10 by way of the keyholes 11, and that the key 16 has been withdrawn from the plugging unit. The rear portion of the housing 15 is wrapped with a jacket 17 which gathers underneath with doubled wings 18, these leading into the first keyhole 11 and retaining the housing 15 against turning motion. However, the key 16 is intended to be given turning motion and therefore receive a swivel eye 20 for attachment to a chain, tag or other holder.

15 The principle of the plugging device is to introduce a pair of folded hinge plates into the lock 10 by way of the receiving keyhole, and then to have such plates spread and form a bar against the retraction or advance of the plugging unit. With the latter lodged in the lock no ordinary key can be inserted into the same from either side of the door.

20 To operate as described, the plugging device is constructed substantially as shown in Figs. 5 to 7. In these figures it is indicated that the housing 15 contains a tubular slide 22 which is thickened at its rear end as indicated at 23 and tapped as shown at 24 to receive a screw 25 extended from a stem 26 forming a reduction of the key 16. The slide 22 has registering diametrical slots 27 through which a cross-pin 28 carried by the housing 15 passes. Thus, when the key 16 is inserted into the rear end of the housing as indicated in Fig. 5, with the screw 25 directed toward the tapped bore 24, the stem 26 makes a sliding fit in such end and starts the screw 25 in the bore 24 as the shoulder formed by the stem on the key 16 meets the housing. With the key in threading rotation, the thickened portion 23 acts as a traveling nut to move the slide rearwardly. It follows, therefore, when the turning of the key 16 is reversed, that the movement of the slide is forward until it rides off the screw 25, in which event the key 16 can be retracted and removed.

25 The hinge plates previously referred to are indicated at 30 in Figs. 5 and 7; and Fig. 6 shows their alternate hinge ears 31 journaled on a center rod 31a carried by a plug 32 which forms a frontal closure for the housing. A slide bar 33 is located beneath the housing 15 and operates in a slot 33a in the wings 18. The slide bar is connected for motion with the slide 22 by a stud 34 which is fitted into a thickened medial portion 35 of the slide. Clearance for the stud is made

by a bottom slot 36 made in the housing 15. The slide bar 33 has its forward end in the form of a wedge 37. An outward extension 38 of the stud 34 serves as an anchor for a hairpin spring 39 whose arms spread against the inner faces of the hinge plates 30, threading through openings 40 in the same. The hairpin spring is thus retained in engagement with the hinge plates, and its function is to lead with a spreading influence on the hinge plates before the wedge enters between them.

A compression spring 45 between the hinge ears 31 and the front end of the slide 22 serves to urge the latter to the forward position shown in Figs. 5 and 6. This action also advances the wedge 37 between the hinge plates 30 to spread them as indicated in Figs. 5 and 7. However, the rearward motion of the slide acts to gather the hinge plates through the agency of oblique cams 46 formed by a longitudinal V-cut made in the bottom wall of the slide; and the backing of the slide withdraws the wedge 37 at the same time to allow the hinge plates to gather.

It has been mentioned that the plugging unit is ordinarily carried by the key 16. Since the latter is necessarily joined to the unit by the screw 25 threaded into the slide, it follows that the hinge plates 30 are in gathered relation, making the plugging device compact enough to be carried in the pocket or from a key ring or chain. Now, in case it is desired to plug the door lock from the outside when leaving or from the inside when retiring it is only necessary to insert the plugging unit into the lock from the corresponding side of the door and rotate the key 16 in the unthreading direction. As this is done, the spring 45 bears forwardly on the slide, urging it to ride off the screw 25. At the same time the slide cams 46 become more widely spaced, permitting the arms of the hairpin spring 39 to urge the hinge plates apart. The advance of the slide then interposes the wedge 37 to positively spread the plates apart and form a plug for the lock. By this time the key has been removed and may be kept in the pocket, a drawer or any other convenient place until its application to the plugging unit for the removal of the same is again required.

It is now apparent that the novel plugging device is a simple and compact accessory capable of application to any mortise type door lock to render the same proof against attempts to open it with a conventional key. Also, the device may be made with a wide variety of combinations in respect to dimensions and fit between the key and the plugging unit, so as to discourage duplication of keys or plugging units by unscrupulous persons. Finally, the device is constructed on well established mechanical principles, has few parts, and may be mastered and used with facility by the average person.

While I have described the invention along specific lines, various minor changes or refinements may be made therein without departing from its principle, and I reserve the right to employ all such changes and refinements as may come within the scope and spirit of the appended claims.

I claim:

1. A plugging device for mortise-type door locks comprising a unit having a pair of hinged plates folded sufficiently close to permit the insertion of the unit into the lock through either keyhole when the unit is assembled with a control, means effective on said plates when the control is re-

5 moved to expand them and constitute the unit a plug barring the insertion of a regular key into the lock, said means comprising a slide with a cam formation effective to gather said plates when the slide moves in the direction of said control, and a connection between the latter and the slide to procure said movement thereof.

2. A plugging device for mortise-type door locks comprising a unit having a pair of hinged plates folded sufficiently close to permit the insertion of the unit into the lock through either keyhole when the unit is assembled with a control, means effective on said plates when the control is removed to expand them and constitute the unit 10 a plug barring the insertion of a regular key into the lock, said unit including a housing, said means comprising a slide with a cam formation effective to gather said plates when the slide moves in the direction of said control, the latter finding a bearing in the housing, other means checking the slide from rotary movement relative to the housing, and a threading connection between the control and the slide effective to move the same as stated when the control is rotated accordingly.

3. A plugging device for mortise-type door locks comprising a unit having a pair of hinged plates folded sufficiently close to permit the insertion of the unit into the lock through either keyhole 15 when the unit is assembled with a control, means effective on said plates when the control is removed to expand them and constitute the unit a plug barring the insertion of a regular key into the lock, said unit including a housing, said 20 means comprising a slide with a cam formation effective to gather said plates when the slide moves in the direction of said control, the latter finding a bearing in the housing, the slide having a tapped bore opposite the control, and 25 a screw extended from the latter and adapted to thread into said bore when the control is rotated in a given direction to procure the said movement on the part of the slide.

4. A plugging device for mortise-type door locks comprising a unit having a pair of hinged plates folded sufficiently close to permit the insertion of the unit into the lock through either keyhole when the unit is assembled with a control, means effective on said plates when the control is removed to expand them and constitute the unit 30 a plug barring the insertion of a regular key into the lock, said means comprising a slide with a cam formation effective to gather said plates when the slide moves in the direction of said control, the latter finding a bearing in the housing, the slide having a tapped bore opposite the control, and 35 a screw extended from the latter and adapted to thread into said bore when the control is rotated in a given direction to procure the said movement on the part of the slide.

5. A plugging device for mortise-type door locks comprising a unit having a pair of hinged plates folded sufficiently close to permit the insertion of the unit into the lock through either keyhole when the unit is assembled with a control, means effective on said plates when the control is removed to expand them and constitute the unit 40 a plug barring the insertion of a regular key into the lock, said means comprising a slide with a cam formation effective to gather said plates when the slide moves in the direction of said control, a connection between the latter and the slide to procure said movement thereof, and 45 yieldable means urging the slide in a direction opposite from said control.

6. A plugging device for mortise-type door locks comprising a unit having a pair of hinged plates folded sufficiently close to permit the insertion of the unit into the lock through either keyhole when the unit is assembled with a control, means effective on said plates when the control is removed to expand them and constitute the unit 50 a plug barring the insertion of a regular key into the lock, said means comprising a slide with a cam formation effective to gather said plates when the slide moves in the direction of said control, a connection between the latter and the slide to procure said movement thereof, and a compression spring interposed between said plates and the end of the slide remote from said control, such spring being effective to urge the 55 slide in a direction opposite from said control.

6. A plugging device for mortise-type door locks comprising a unit having a pair of hinged plates folded sufficiently close to permit the insertion of the unit into the lock through either keyhole when the unit is assembled with a control, means effective on said plates when the control is removed to expand them and constitute the unit a plug barring the insertion of a regular key into the lock, said means comprising a slide with a cam formation effective to gather said plates when the slide moves in the direction of said control, a connection between the latter and the slide to procure said movement thereof, and means carried by the slide and effective to separate said plates on the return movement of the slide.

7. A plugging device for mortise-type door locks comprising a unit having a pair of hinged plates folded sufficiently close to permit the insertion of the unit into the lock through either keyhole when the unit is assembled with a control, means effective on said plates when the control is removed to expand them and constitute the unit a plug barring the insertion of a regular key into the lock, said means comprising a slide with a cam formation effective to gather said plates when the slide moves in the direction of said control, a connection between the latter and the slide to procure said movement thereof, yieldable means carried by the slide to urge the said plates apart on the departure of said cam formation, and positive means also carried by the slide and entering between said plates to spread them apart.

8. A plugging device for mortise-type door locks comprising a unit having a pair of hinged plates folded sufficiently close to permit the insertion of the unit into the lock through either keyhole when the unit is assembled with a control, means effective on said plates when the control is removed to expand them and constitute the unit a plug barring the insertion of a regular key into the lock, said means comprising a slide with a cam formation effective to gather said plates when the slide moves in the direction of said control, a connection between the latter and the slide to procure said movement thereof, a hairpin spring with its arms urging the plates apart on the departure of said cam formation, and a wedge also carried by the slide and entering between said plates to spread them apart.
